John W. Timmons, 909 E. Main St., Greenville, Ohio

Filed Sept. 12, 1961, Ser. No. 66,722

Term of patent 14 years

(Cl. D78—1)

FIG. 1 is a top plan view of a valve for water conditioner systems, showing my new design;

FIG. 2 is a side elevation thereof;

FIG. 3 is an elevation thereof as seen from the opposite side of FIG. 2;

FIG. 4 is a bottom plan view thereof.

FIG. 5 is an end elevation thereof; and

FIG. 6 is an elevation thereof as seen from the opposite side of FIG. 5.

The solenoids are shown in FIGS. 1, 2, 3, 5 and 6 for illustrative purposes only.

I claim:

The ornamental design for a valve for water conditioner systems or the like, as shown and described.
